UNITED STATES PATENT OFFICE.

CHARLES L. CLARK, OF PITTSBURGH, PENNSYLVANIA, ASSIGNOR TO A. BISHOP CHANCE, OF CENTRALIA, MISSOURI.

DESIGN FOR A COMBINED POLE-LINE WRENCH AND HAMMER.

Application filed April 2, 1928. Serial No. 26,090. Term of patent 14 years.

To all whom it may concern:

Be it known that I, CHARLES L. CLARK, a citizen of the United States, residing at Pittsburgh, in the county of Allegheny and State of Pennsylvania, have invented a new, original, and ornamental Design for a Combined Pole-Line Wrench and Hammer, of which the following is a specification, reference being had to the accompanying drawings, forming part thereof.

Referring to the drawings:

Figure 1 is a side elevational view of the

combined pole line wrench and hammer showing my new design.

Figure 2 is a top plan view of the same.

Figure 3 is an end elevational view of the same.

I claim:

The ornamental design for a combined pole line wrench and hammer, as shown.

In witness whereof I hereunto subscribe my name this 16th day of March, 1928.

CHARLES L. CLARK.
